UNITED STATES PATENT OFFICE.

ADOLPH GEIGER, OF ROCHESTER, NEW YORK.

CUTTING-DIE.

1,185,898.

Specification of Letters Patent. Patented June 6, 1916.

Application filed September 17, 1915. Serial No. 51,135.

To all whom it may concern:

Be it known that I, ADOLPH GEIGER, a citizen of the United States, residing at 635 Joseph avenue, in the city of Rochester, 5 county of Monroe, and State of New York, have invented certain new and useful Improvements in Cutting-Dies, of which the following is a specification.

My invention relates to improvements in 10 cutting dies and more particularly to dies of this class for forming top lifts for heels for articles of foot wear.

My present invention is an improvement upon the cutting dies described and claimed 15 in Letters Patent No. 1,129,478, granted to me February 23rd, 1915, and the objects are to simplify the construction and reduce the number of parts and to so arrange the same that a high pressure can be applied and a 20 dense lift produced. These and other objects I accomplish as hereinafter set forth in the following description and particularly pointed out in the appended claims, reference being had to the accompanying 25 drawings in which adaptations or embodiments of my improved dies are shown.

In the drawings Figure 1, represents a side elevation of my improved device. Fig. 2, is a central longitudinal section on line 2—2 Fig. 3. Fig. 3, is a detached top plan view of the cutting die. Fig. 4, is a transverse section through the cutting die. Fig. 5, is a detail detached plan view of the guide block. Fig. 6, is a central longitudinal section 35 through a form of my improved device employed for soft leather. Fig. 7, is a detail detached view of one of the rubber disks employed in the form shown in Fig. 5. Fig. 8, is a detached top plan view of one form of cutting die. Fig. 9, is a transverse section 40 through the form of cutting die shown in Fig. 8, taken on line 9 in said Fig. 8. Fig. 10 is a detached bottom view of the holding die or member.

45 In referring to the embodiments of my invention shown in the accompanying drawings in detail, like numerals indicate corresponding parts.

A tubular casing 1, is provided on the exterior of its upper terminal with screw threads 2, and on the interior of its lower terminal with screw threads 3. This casing constitutes a handle which can be readily grasped by the operator and is preferably 50 knurled or roughened upon its medial ex-

terior surface to prevent slipping and provide a more secure grip.

A screw nut 4, is screwed upon the screw threaded upper terminal of the casing and is provided at the top with an inwardly extending annular flange 5, which projects over the top edge of the casing and inwardly sufficiently to form an annular shoulder extending within the top mouth of the casing as shown in Fig. 2. This nut 4 is preferably 60 knurled on its periphery as shown at 5^a, in Fig. 1, so that it may be easily turned by hand.

A cutting die 5^b of hollow formation and of substantially the shape of the heel of a 70 shoe is provided with thickened portions 6, having deep internally screw threaded recesses 7, as shown in Fig. 4.

A guide block or disk 8, is mounted upon the top of the cutting die being rigidly fastened thereto by screws 9, which are fitted through counter-sunk openings in the block 8, and screw into the recesses 7. The block or disk 8, has a tubular perpendicular extension 10, which is exteriorly screw threaded 75 and screws into the lower end of the casing 1.

A two membered plunger is slidably mounted within the casing and cutting die, being composed of a lower member having a 85 holding block 11, shaped to substantially the interior conformation of the cutting die and a stem 12, provided with a screw threaded recess in its upper end, and an upper member having a head 13, and a screw threaded shank 14, which screws into the recess in the stem of the lower member.

The guide block or disk 8, is provided with an opening 15, through which the stem 12, fits and slides.

The top of the extension is recessed as shown at 16, said recess being considerably larger than and concentric with the opening through the extension and being adapted to receive the head 13, when the 95 plunger is in its lowermost position.

The plunger is yieldingly maintained in its holding position by a heavy helical or coil spring 17, which is arranged within the casing with its upper extremity bearing 105 against a top disk 18 which in turn fits against the flange 5 of the top nut 4, and its lower end pressing upon the head 13 of the plunger.

To center the head 13 with respect to the 110

spring, I prefer to form a raised center portion 19 on the head which fits in the lower end of the spring.

The raised portion 19, may be provided 5 with a slot 20 for the reception of a suitable turning tool such as a screw driver so that the members of the plunger may be readily taken apart. As shown in Fig. 2, I prefer to round the curved bottom edge of the 10 plunger as otherwise owing to the heavy pressure exerted by the spring, the lift would be apt to be cut. Also I prefer to bevel the curved part 22, of the cutting die on the inside while the inner edge of the 15 breast 23, is left straight.

To provide means for conveniently lubricating the interior I form an oil groove 24, on the top edge of the cutting die.

In the form of my invention shown in 20 Figs. 6 and 7, which is chiefly adapted for comparatively soft leather requiring lighter pressure, a series of annular disks 25 of rubber or other suitable resilient material are substituted in place of the spring 17, 25 and are fitted between the top disk and the head of the plunger. A series of metal washers 26, are interposed between and separate the disks and a metal bottom disk 27, is arranged below the lowermost rubber 30 disk and has a flat top surface against which the lowermost rubber disk presses. As shown in Fig. 6, the bottom disk 27, seats in the recess 16, when in its lower position.

35 To avoid any possibility of the cutting die breaking out under heavy work especially at the corners between the curved cutting edge and the straight cutting edge forming the breast of the lift, I may round 40 these corners and attach a separate cutting plate to the interior of the straight cutting edge. This form of my invention is shown in Figs. 8 and 9.

The separate cutting plate 28, is attached 45 to the inner surface of the breast of the die by countersunk screws 29, and has its lower sharpened edge 30, beveled to form a continuation of the outer beveled edge of the cutting die and its side edges 31, rounded 50 to fit in and conform to the rounded corners of the die.

If desired, any suitable figure may be stamped in the bottom side of the plunger which will be imprinted in the surface of 55 the top lift.

This improved device can be easily and quickly assembled and dismounted.

In operating the device the plunger forms 60 a holding die which is driven back within the cutting die against the tension of the spring or rubber disks as the pressure becomes great enough, thereby permitting the cutting die to be forced down to cut the desired blank.

65 While I have illustrated and described

preferred forms of construction for carrying my invention into effect, this is capable of a wide range of variation, alteration, modification and change without departing from the spirit of my invention, I therefore do not wish to be limited to the construction herein shown and described, but desire to avail myself of all such variations, alterations, modifications and changes as fairly fall within the scope of the appended 70 claims or may be construed to be within the scope thereof by involving the doctrine of equivalents.

What I claim as my invention and desire to secure by Letters Patent is:—

1. A device of the class described, comprising a tubular casing, a guide block attached to the lower end of the casing and having an opening, a cutting die attached to the guide block, a holding die yieldingly mounted in the cutting die and having a stem projecting through the opening in the guide block and into the casing and a spring in the casing bearing against the stem of the holding die.

2. A device of the class described, comprising a tubular casing, a guide block attached to the lower end of the casing and having an opening, a cutting die attached to the guide block, a holding die yieldingly mounted in the cutting die and having a stem projecting through the opening in the guide block and into the casing, an enlargement at the upper extremity of said stem and a spring in the casing bearing against 100 the enlargement of the stem.

3. A device of the class described, comprising a tubular casing, a guide block attached to the lower end of the casing, a cutting die attached to the undersurface of 105 the guide block, a holding die yieldingly mounted in the cutting die and having a stem projecting through an opening in the guide block into the casing, and resilient means within the casing against which the 110 stem contacts.

4. A device of the class described, comprising a tubular casing, a guide block attached to the lower end of the casing, a cutting die attached to the guide block, a 115 resilient element within the casing and a separable multi-membered plunger having the lower member yieldingly mounted in the cutting die and constituting a holding die with its stem projecting through an opening 120 in the guide block and an upper member having a head engaging the resilient element.

5. A device of the class described, comprising a casing, guiding means at the lower 125 end of the casing, a cutting die attached to the guiding means, a holding die yieldingly mounted within the cutting die and having a stem projecting through the guiding means and into the casing, and having 130

an enlarged head within the casing and tensioning means within the casing bearing against the enlarged head of the stem.

6. The combination with a casing, a guide block at one end of the casing and a cutting die attached to the guide block of a yielding holding die within the cutting die having a stem extending through the guide block and tensioning means within the casing bearing against said stem.

7. A device of the class described, comprising a hollow cutting die, a holding die yieldingly mounted within the cutting die, a guide block at the top of the cutting die for guiding said holding die, and means located above the guide block for tensioning said holding die.

8. A device of the class described, comprising a hollow cutting die, a holding die yieldingly mounted within the cutting die, a guide block at the top of the cutting die, a casing attached to the guide block opposite the cutting die and means located within said casing for tensioning said holding die.

25 9. In a device of the class described, a

casing having an internally screw threaded lower end, a guide block having a tubular extension screwing in the lower end of the casing, a cutting die attached to the guide block, a holding die movably mounted within the cutting die and having a stem projecting through the tubular extension of the guide block, and tensioning means in the casing bearing against said stem.

10. In a device of the class described, a casing having an internally screw threaded lower end, a guide block having a tubular extension screwing in the lower end of the casing, a cutting die attached to and extending below the guide block, a holding die movably mounted within the cutting die and having a stem projecting through the tubular extension of the guide block, a retaining nut on the upper terminal of the casing, and tensioning means in the casing bearing against said stem.

In testimony whereof I have this day set my hand.

ADOLPH GEIGER.
